UNITED STATES PATENT OFFICE.

THEODORE E. REYNOLDS, OF CINCINNATI, OHIO.

PUMP.

Application filed March 24, 1923. Serial No. 627,489.

To all whom it may concern:

Be it known that I, THEODORE E. REYNOLDS, a citizen of the United States of America, and a resident of Cincinnati, in the county of Hamilton and State of Ohio, have invented a new and useful Improvement in a Pump, of which the following is a specification.

An object of my invention is to provide a simple and efficient pump of the type ordinarily used for inflating vehicle tires and the like.

Another object of my invention is to provide a device of the class referred to wherein the pump elements positively position a flexible element of the piston for attaining a maximum efficiency for the device.

Another object of my invention is to provide means for effecting a knife or feather edge upon the referred to flexible member.

Another object of my invention is to provide a device wherein injury to the referred to flexible element at the end of the compression stroke is avoided.

Another object of my invention is to provide an automatic and efficient valve controlling admission to the compression chamber of the pump.

These and other objects are attained by the means described herein and disclosed in the accompanying drawings, in which:

The figure is a transverse sectional view of a pump embodying my invention.

The base 1 may be of any suitable structure and carries the ordinary barrel or cylinder 2 having a cap 3 through which reciprocally extends the stem 4 carrying the compression member or piston 5 disposed within the bore of the barrel. The piston 5 is capable of a slight movement longitudinally of the stem 4. This slight relative movement is employed for seating and unseating the valve face 6 formed on the lower end of the stem 4, upon the seat 7 formed on the piston. The piston comprises the sleeve 8 having an axial bore into which stem 4 extends, and from which the stem is precluded from separation by means of a pin 9 carried by the sleeve and extending into the annular groove 10 formed upon the lower end of the stem 4. The sleeve has formed in it a transversely extending bore 11 that communicates with the conical bore 12 formed at the upper end of the screw plug 13 carried by the lower end of the sleeve 8. The screw plug has an axial bore

14 communicating with the conical bore 12. The wall of the conical bore 12 forms the sleeve seat 7 and is engaged by the valve face 6, when the piston is moved downwardly in the barrel. When the piston is moved upwardly through the barrel, the valve 6 is opened and communication between the chambers formed on opposite sides of the piston 5 is established through the bore 11 in the sleeve 8 and the axial bore in the screw plug. A suitable washer 15 is interposed between the flanged lower end 16 of the screw plug 13 and the lower end of the sleeve 8, and serves as a base or foundation upon which the flexible washer 17, preferably of leather, is clamped by the screw plug 13. A suitable handle 18 is provided for reciprocating the piston. The base carries a block 19 upon which is disposed a sliding plate 20. The sliding plate 20 is substantially a truncated cone. The movement of the plate 20 is rather limited, any suitable means being employed for precluding separation of the sliding plate 20 and the base 1, for example by countersinking the aperture 21 through the plate 20, within which aperture 21 is contained a conical headed pin 22 secured in position by a suitable screw 23 extending through the base. The movement of the plate 20 relatively to the block 19 is slight, wherefore the plate 20 is at all times substantially coaxial with the barrel and the piston. A duct 24 communicating with the lower most portion of the chamber below the piston may communicate with a suitable tube or hose 25. A check valve 26 controls communication between the tube 25 and the duct 24.

In the operation of my device, the piston is reciprocated as is common, and the valve 6 is alternately opened and closed, the valve being opened on the upstroke and closed on the down stroke. When the piston reaches its lower limit the similar face 27 of the flexible washer 17 engages the conical face 28 formed on the sliding plate 22, wherefore the flexible washer is pushed outwardly for effecting a positive circumferential seal upon the inner wall of the barrel tube. The repeated engagement of the face 27 of the flexible washer upon the plate 20 serves to develop a taper face upon the lower edge of the flexible washer, this taper face converging upwardly.

In devices heretofore employed, it was

practically impossible to secure a sealing contact of the flexible washer upon the inner face of the barrel because when the piston was inserted in the barrel there was no way in which flutes in the flexible washer could be eliminated, wherefore air undergoing compression would escape upwardly past the piston. When employing my device, the contact of the flexible washer upon the yielding or sliding plate 22 serves to positively carry the flexible washer outwardly throughout its entire circumference thereby effecting annular contact of the flexible washer upon the cylinder wall. The development of the 10 tapered lower edge on the washer 17 makes this lower edge very flexible, wherefore the compression below the piston serves to augment the seal of the flexible washer upon the barrel because this compression force tends 15 to push such highly flexible lower end of the washer tightly against the barrel, thereby precluding loss of compression between the barrel and the flexible washer. The capacity for slight relative movement of the sliding plate 20 permits the conical face 28 of the plate 22 to automatically center itself within the tapered inner face 27 of the flexible washer at the end of each down stroke 20 of the piston. This centering action is rendered very gentle by reason of the compression present below the piston as the flexible washer reaches the bottom of its stroke and thus eliminates the undue wear and premature destruction which is present in fixed and 25 rigid washer conditioning means which are known to the applicant.

What I claim is:

1. In a device of the class described the combination of a barrel, a reciprocating piston in the barrel comprising a flexible wash-

er, and a sliding plate at the base of the barrel for engagement with the inner face of the flexible washer for effecting positive annular seating of the washer upon the barrel.

2. In a device of the class described the combination with a pump comprising a barrel and a reciprocating piston in the barrel having a flexible washer, of self-centering means within the barrel for engagement upon the inner face of the washer and for effecting positive annular contact of the outer face of the washer upon the barrel.

3. In a device of the class described the combination of a barrel, a stem reciprocally contained in the barrel, a sleeve mounted on the stem for limited movement longitudinally of the stem and carrying a flexible washer dividing the barrel into a pair of chambers, and a valve and valve seat associated with the stem and the sleeve for utilizing the relative movement of the stem and the sleeve for controlling communication between the chambers on opposite sides of the washer, and slidable means for positively effecting annular contact of the flexible washer upon the wall of the barrel.

4. In a device of the class described the combination of a base, a barrel carried by the base, a plate substantially co-axial with the barrel carried by the base and capable of a limited movement radially of the barrel and a piston reciprocally contained in the barrel comprising a flexible washer for engagement upon the sliding plate for effecting annular contact of the flexible washer upon the barrel wall.

In testimony whereof, I have hereunto subscribed my name this 12th day of March, 1923.

THEODORE E. REYNOLDS.
